ELECTRON DECELERATOR

Richard F. Baker, Merchantville, N. J., assignor
to Radio Corporation of America, a corporation
of Delaware

Application March 23, 1942, Serial No. 435,827

11 Claims. (Cl. 250—49.5)

This invention relates generally to electron decelerators and particularly to methods of and apparatus for decelerating and diffusing electrons in electron microscopes for the purpose of obtaining optimum electron velocity for the exposure of sensitized emulsions or for forming electronic images.

It has been customary to accelerate the electrons irradiating the object in an electron microscope to velocities at which the electrons pierce the object. In many instances, such velocities require accelerating voltages in excess of 100 kilovolts. Experiments indicate that such velocities are inefficient for exposure of photographic emulsions, since the optimum velocity for this purpose is produced by accelerating voltages of approximately 80 to 100 kilovolts, depending on the emulsion characteristics. Velocities substantially above or below this critical value produce less effect upon photographic emulsions and therefore require longer exposure for a given image density. Therefore it is desirable to irradiate the object or otherwise utilize the electron beam at the most advantageous velocity and then alter the velocity to the optimum value for exposure of the sensitized emulsion.

An object of this invention is to provide a method of and means for changing the velocity of an electron beam in an electron microscope or other electronic device prior to the impingement of the electrons on a photographically sensitized emulsion. Another object is to provide means for changing the velocity of electrons to the optimum value required for exposure of a sensitized emulsion or for forming electronic images. Still another object is to provide in an electron microscope, or similar electronic device, a velocity controlling device for altering the velocity of electrons impinging on the sensitized emulsion of a photographic target. Another object is to provide a screen having desired electron scattering or diffusion characteristics.

The invention will be described with reference to the drawing of which Figure 1 is a cross-sectional view of a support containing a sensitized emulsion and an electron decelerator; Figure 2 is a schematic diagram of an electron decelerator in combination with typical electronic apparatus; Figure 3 is a schematic diagram of another embodiment of the invention; and Figure 4 is a graph of the electron sensitivity characteristics of a typical photographic emulsion. Similar reference numerals are applied to similar elements throughout the drawing.

Referring to Fig. 1, a base 1 containing a photo-

graphic emulsion 2 which is sensitive to electron bombardment is shown in the field of an electron beam 4. An electron decelerator 3, which may consist of one or more thin layers of metal foil, oil, paint, or suitable cellulose material, is located between the sensitized emulsion and the source of the electron beam. The decelerator material should be of high atomic number, and should be located adjacent to or in contact with the photographic emulsion layer. The plural layers may be in intimate contact or separated a predetermined distance.

Fig. 2 is any electronic device in which an electron beam is caused to expose a photographic emulsion. An electron source 10 is supplied with power from a battery or other source or voltage 7. Electrons emitted by the source 10 are drawn toward an accelerating electrode 6 supplied with a high positive potential from the source 8. The accelerating electrode causes the electron beam to penetrate and pass through the object or specimen 13. An electrostatic or magnetic electron focusing means 9 causes the electron beam to be focused upon the photographically sensitized surface 2 of the base 1. Since the velocity of the electrons 4 required for penetration of the object 13 is considerably higher than the optimum electron velocity for exposure of the photographic emulsion, one or more layers 3 of an electron permeable material which may be metal foil, oil, paint, cellulose or the like is interposed between the objective and the sensitized emulsion to reduce the average velocity of the electrons in the electron beam 5 to the optimum value, and cause diffusion of the electrons throughout the emulsion. The decelerator 3 should be located as close as possible to the emulsion layer 2 if good image definition is desired.

Fig. 3 is a device similar to that described in Fig. 2 with the exception that a cylindrical decelerating electrode 11 connected to a suitable negative potential 12 decelerates the electron beam before impingement upon the sensitized emulsion 2. In this embodiment, the decelerating electrode 11 is substituted for the decelerating means 3 in the device of Fig. 2.

The decelerating electrode 11 should be at suitable negative potential to decelerate the electron beam to an optimum velocity. This embodiment will permit desired electron deceleration without causing undesired electron scattering or diffusion inherent in the decelerating means of Fig. 2. Freedom from electron scattering is particularly important when electron images of high definition are desired. If some degree of elec-

tron scattering is found advantageous in particular apparatus, this may be readily accomplished by the addition of a thin metal foil or grid element 14 connected to, and preferably located inside, the electrode 11. The characteristics of the foil or grid will determine the degree of scattering and will also contribute to the deceleration. It should be understood that the electrode 11 also can be used for accelerating the electron beam to optimum velocity by connecting it to a suitable source of positive potential instead of the negative potential 12. This embodiment per se is claimed in application Serial No. 435,788, filed March 23, 1942, by James L. Whitaker and assigned to the same assignee.

Fig. 4 is a graph S which indicates the sensitivity of a typical photographic emulsion to electron velocities produced by accelerating voltages from 0 to 300 kilovolts. It is apparent that the emulsion sensitivity commences at about 3 kilovolts and continues to rise to a maximum at approximately 80 kilovolts after which it drops to a relatively low value as the accelerating voltage is increased. The optimum value of voltage varies somewhat with emulsion characteristics. The decelerator means, should be of predetermined thickness, depending on the material used, to reduce the electron velocity to the optimum value.

It will be seen that the means which have been described operate on an entirely different principle than typical optical filters, in that this invention controls the velocity and diffusion of the electrons impinging on a photographic emulsion while optical filters control either the frequency or the intensity of the light beam applied to the emulsion. Experiments indicate that the effect described is probably not due to secondary emission in the velocity control element or to fluorescence or radiation from the decelerator or the photographic emulsion. While no attempt has been made to explain the reasons for the relation between photographic emulsion sensitivity and electron velocity, experimental data clearly shows that the relation exists, and that electron velocity can be controlled for optimum emulsion efficiency by the means and methods disclosed as by this invention.

I claim as my invention:

1. In electronic apparatus including an evacuated chamber, a photographically sensitized electron target disposed within said evacuated chamber, electron velocity changing means and electron diffusing means disposed in the electron path adjacent said target, the method comprising directing said electrons at said target, changing the velocity of said electrons to an optimum value for the exposure of said target and diffusing said electrons throughout the sensitized portion of said target.

2. In an electron microscope, including an evacuated chamber, an object and a photographically sensitized target disposed within said chamber, the method comprising accelerating said electrons to penetrate said object, focusing the electron image of said object on said target, and altering the velocity of the electrons of said image to the optimum value for the exposure of said target.

3. In electronic apparatus including an evacuated chamber, a source of electrons, means for accelerating said electrons, electron focusing means, an object, means for decelerating said electrons, and a photographically sensitized target disposed within said chamber, the method comprising accelerating said electrons, focusing

said electrons on said object to form an image thereof, directing said image at said target, and changing the velocity of said electrons between said object and target to the optimum value for the exposure of said second target.

4. In electronic apparatus including an evacuated chamber, a source of electrons, means for accelerating said electrons, a photographically sensitized target disposed within said chamber and means for directing said electrons at said target, means disposed between said source and said target comprising at least one thickness of electron permeable material to decelerate substantially all of said electrons an amount to provide optimum photographic exposure of said target.

5. In electronic apparatus including an evacuated chamber, a source of electrons, means for accelerating said electrons, a photographically sensitized target disposed within said chamber and means for directing said electrons at said target, means disposed between said source and said target comprising at least one thickness of a dense material to decelerate substantially all of said electrons an amount to provide optimum photographic exposure of said target.

6. In electronic apparatus including an evacuated chamber, a source of electrons, means for accelerating said electrons, a photographically sensitized target disposed within said chamber and means for directing said electrons at said target, means disposed between said source and said target comprising at least one thickness of a metallic foil to decelerate substantially all of said electrons an amount to provide optimum photographic exposure of said target.

7. In electronic apparatus including an evacuated chamber, a source of electrons, means for accelerating said electrons, a photographically sensitized target disposed within said chamber and means for directing said electrons at said target, means disposed between said source and said target comprising at least one thickness of a cellulose material to decelerate substantially all of said electrons an amount to provide optimum photographic exposure of said target.

8. In electronic apparatus including an evacuated chamber, a source of electrons, means for accelerating said electrons, a photographically sensitized target disposed within said chamber and means for directing said electrons at said target, means disposed between said source and said target comprising at least one thickness of electron permeable material to decelerate substantially all of said electrons to a value which is a function of the thickness of said material for optimum exposure of said target.

9. In electronic apparatus including an evacuated chamber, a source of electrons, means for accelerating said electrons, a photographically sensitized target disposed within said chamber and means for directing said electrons at said target, means disposed between said source and said target comprising at least one thickness of a dense material to decelerate substantially all of said electrons to a value which is a function of the thickness of said material for a predetermined exposure of said target.

10. In electronic apparatus including an evacuated chamber, a source of electrons, means for accelerating said electrons, a photographically sensitized target disposed within said chamber and means for directing said electrons at said target, means disposed between said source and said target comprising at least one thickness of a metallic foil to decelerate substantially all of

said electrons to a value which is a function of the thickness of said foil for optimum exposure of said target.

11. In electronic apparatus including an evacuated chamber, a source of electrons, means for accelerating said electrons, means disposed within said chamber for supporting a photographically sensitized target and means for directing

5 said electrons at said target, means disposed between said source and said target comprising at least one thickness of a cellulose material to decelerate substantially all of said electrons to a value which is a function of the thickness of said material for optimum exposure of said target.

RICHARD F. BAKER.
